UNITED STATES PATENT OFFICE.

PAUL HEYMANN, OF PARIS, FRANCE.

PERFUME SET.

Application filed June 28, 1928. Serial No. 288,831.

This invention relates to improvements in perfume sets or packages and has for its object the provision of a novel form of perfume container in which the perfume contents are so arranged as to simulate a jewelled necklace or similar article.

Another object of the invention is the provision of a perfume container in which the stoppers of the individual bottles of perfume are also employed in creating a novel decorative effect.

Further objects of the invention will be apparent from the specification and drawings in which

Fig. 1 is a perspective view of my improved perfume set or container with the outer cover lifted.

Fig. 2 is a perspective view of the same set with the inner cover lifted exposing the individual bottles of perfume.

Fig. 3 is a top plan view of the set shown in Fig. 2.

Fig. 4 is a sectional view along the line 4-4 of Fig. 3.

My improved container consists of a base A, a lid B and an inner cover C and when the cover C is in its normal position on the base A, it has the appearance of an ordinary jewelry box or container for mounting a necklace, tiara or similar article. Below the inner cover C, however, is a space for mounting the individual bottles of perfume D, recesses being provided in the base into which the necks of the bottles fit, the stoppers of the bottles normally extending outside of the concavity in the base A between the line of junction of the cover C and the base A, the cover C and the base A having such concavities formed therein so that said stoppers can protrude therethrough without revealing any opening between the cover C and the base A.

The heads of the stoppers of these perfume bottles are cut or faceted like precious stones as will be seen more clearly in Figs. 2 and 3. Between these stopper heads at the line of intersection between the cover and the base, when the cover C is depressed, I then insert a row of rhinestones E which fill up the spaces between the individual stoppers F so as to give the illusion of a jewelled necklace. These rhinestones are glued, pinned or otherwise fastened either to the cover C or to the base at the line of intersection between the cover and the base so as to conceal said line of intersection so that when the row of stopper

heads and rhinestones are alternately exposed, the meeting line between the inner cover C and the base is effectually concealed and a perfect illusion of a necklace resting in a jewel box is produced by the arrangement hereinbefore described.

It is apparent also that for the rhinestones E, pearls or beads of other stones or imitations thereof may be used.

It is also apparent that instead of the stopper head illustrated which simulates a cut emerald, other designs varying both as to shape and color may be used without departing from the spirit of my invention.

It is also apparent that the same effect may be produced by using other shapes of containers as I am not restricted to a round container in producing my improved display, as a similar effect can be obtained with a square or other rectangular box or boxes of other shapes, the essential part of my invention being the employment of the stopper heads to simulate a jewelry element, whilst the bottles themselves are concealed from view and the provision of other jewelry elements to simulate a necklace or similar article.

Having fully described my invention, what I claim is:

1. A display set comprising in combination a base, a lid, an inner cover between said lid and base, a series of bottles arranged on said base and under said inner cover, the heads of said bottles being exposed at the line of intersection between said base and inner cover.

2. A display set comprising in combination a base, a lid, an inner cover between said lid and base, a series of bottles arranged on said base and under said inner cover, the heads of said bottles being exposed at the line of intersection between said base and inner cover and a series of stones placed between the stopper heads at the point of intersection between the inner cover and the base.

3. A display set comprising in combination a base, a lid, an inner cover between said lid and base, a series of bottles arranged on said base and under said inner cover, the heads of said bottles being exposed at the line of intersection between said base and inner cover and a series of stones placed between the stopper heads at the point of intersection between the inner cover and the base so that the stopper heads and stones will simulate a necklace or similar article.

4. A display set comprising a base, a lid, a hinge cover intermediate said base and lid, a series of ornaments placed on the intersection line of said cover and base and a series of stopper heads on said intersection line between said series of ornaments.

5. A display set comprising a base, a lid, a hinge cover intermediate said base and lid,

a series of ornaments placed on the intersection line of said cover and base and a series of stopper heads on said intersection line between said series of ornaments so as to simulate a necklace or similar article.

In testimony whereof I affix my signature.

PAUL HEYMANN.
